(57) **CLAIM**

The ornamental design for a trailer hitch mirror, as shown
and described.

DESCRIPTION

FIG. 1 is a perspective view of a trailer hitch mirror
embodying my new design.

FIG. 2 is a right side view of the mirror of FIG. 1.

FIG. 3 is a left side view of the mirror of FIG. 1.

FIG. 4 is a rear elevation view of the mirror of FIG. 1; and,
FIG. 5 is a top plan view of the mirror of FIG. 1.
The bottom of the mirror does not form a part of the
invention.
